UNITED STATES PATENT OFFICE.

WILLIAM WASSERSTROM, OF NEW YORK, N. Y.

DESIGN FOR A BELT.

SPECIFICATION forming part of Design No. 33,621, dated November 27, 1900.

Application filed November 3, 1900. Serial No. 35,431. Term of patent 3½ years.

To all whom it may concern:

Be it known that I, WILLIAM WASSERSTROM, a citizen of the United States, and a resident of the city of New York, borough of Manhattan, in the county and State of New York, have invented and produced a new and original Design for a Belt, of which the following is a specification, reference being had to the accompanying drawing, forming a part thereof, in which is represented a perspective view, taken from the rear, of a belt embodying the features of my design.

The leading feature of the design consists in an elongated lozenge-shaped panel at the back of a belt and in the representation of a longitudinal back section which is apparently interlaced through the central portion of the panel, whereby vertical sections of the panel are apparently embossed.

The minor features of the design consist in

the top and bottom borders of the said front and interlaced parts of the belt and the marginal border of the panel, together with oppositely-curved lines arranged in pairs and extending transversely of the panel from top to bottom at those portions over the interlaced back section of the belt.

Having thus described my invention, I claim as new and desire to secure by Letters Patent—

The design for a belt herein shown and described.

In testimony whereof I have signed my name to this specification in the presence of two subscribing witnesses.

WILLIAM WASSERSTROM.
